GASOLINE PUMP

Albert E. Spitzberg and Charles E. Hutchins,
Fort Wayne, Ind.

Filed Feb. 26, 1959, Ser. No. 54,751

Term of patent 14 years

(Cl. D52—2)

FIG. 1

FIG. 2

FIGURE 1 is a front perspective view of a gasoline pump showing our new design. The opposite side is substantially plain and the rear of the gasoline pump is substantially of the same appearance as the front shown.

FIGURE 2 is a side elevational view of the gasoline pump shown in FIGURE 1.

We claim:

The ornamental design for a gasoline pump, as shown and described.
